US0D1070064S

(12) **United States Design Patent** (10) **Patent No.:** **US D1,070,064 S**
(45) **Date of Patent:** **** Apr. 8, 2025**

(54) **FAN BLADE**

(71) Applicant: **Delta Electronics, Inc.**, Taoyuan (TW)

(72) Inventors: **Chih-Hui Wu**, Taoyuan (TW);
Kuan-Chen Liu, Taoyuan (TW)

(73) Assignee: **Delta Electronics, Inc.**, Taoyuan (TW)

(**) Term: **15 Years**

(21) Appl. No.: **29/822,982**

(22) Filed: **Jan. 13, 2022**

(51) LOC (15) Cl. **23-03**

(52) U.S. Cl.

USPC **D23/413**

(57) **CLAIM**

The ornamental design for a fan blade as shown and described.

DESCRIPTION

FIG. 1 is a perspective view of a first embodiment of a fan blade showing our new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of a second embodiment of a fan blade;

FIG. 10 is another perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof; and,

FIG. 16 is a bottom plan view thereof.

The broken line portions in the drawing views are included to show unclaimed subject matter only and form no part of the claimed design.

1 Claim, 16 Drawing Sheets
